UNITED STATES PATENT OFFICE

IRWIN STEINBERGER, OF NEW YORK, N. Y., ASSIGNOR TO STEINBERGER BROS. GLOVE CORP., OF NEW YORK, N. Y., A CORPORATION OF CALIFORNIA

ARMLET

Application filed March 19, 1931. Serial No. 523,853.

An object of the invention is to provide an armlet to be worn with a glove, the armlet having a wrist portion under which the upper portion of the glove is normally disposed. 5 The armlet with a glove serves as a mousquetaire and the glove may be removed without displacing the armlet. This avoids the difficulty which a woman must contend with in wearing the usual mousquetaire, for when a 10 mousquetaire is worn the glove portion of the mousquetaire is permitted to hang, or is tucked under the arm portion of the mousquetaire when the hand portion is removed from the hand. In either case this is objectionable. The gloves covering the hands, and 15 which are worn with the armlets which are the subject matter of this application, may be of the same color as the armlets, or the armlets and gloves may be of contrasting 20 colors or materials. With the armlets, which are the subject matter of this application, the gloves worn therewith may be removed without displacing the armlets.

The armlets may be adjusted on a woman's 25 arms more readily than is possible with the arm portions of the mousquetaires and the same armlets may be used with different pairs of gloves. As there is little wear to the armlets and as the gloves are relatively inexpensive, there is a great saving in using the armlets instead of mousquetaires, which are quite 30 expensive.

Inasmuch as the inner ends of the gloves 35 will not be secured to the armlets, there will be some freedom of movement of the wrist portions of the glove relatively to the armlets and the movement of the hands of the wearer will not pull on the armlets to displace the armlets. This avoids another objection 40 to the mousquetaire where the hand portions and the arm portions are of one piece of material and any movement of the hand portion serves to pull on the arm portion of the mousquetaire.

Additional objects of the invention will appear in the following specification in which the preferred form of the invention is described.

In the drawing similar reference charac-

ters refer to similar parts in all the views, of which

Figure 1 is a perspective view illustrating the manner in which the armlet may be worn with a glove, 55

Figure 2 is a view showing in elevation the armlet,

Figure 3 is a sectional fragmentary view illustrating the manner in which the lower portion of the armlet is constructed, and 60

Figure 4 is a view showing a modified form of the invention.

By referring to the drawing it will be seen that the armlet A is preferably made of one piece of material with a longitudinally extending seam 10 which preferably is disposed at the underside of the armlet. The bottom of the armlet A is turned outwardly and upwardly at 11 and is secured to the body of the armlet by stitching or by other means at 12, 65 the turned-out portion extending outwardly and downwardly at 13 to 14, the stitches at 12 engaging the turned-in portion of the armlet adjacent its upper point 15 to hold the parts in position, as illustrated in Figure 3 70 75 of the drawing.

In the tunnel 16 formed by the outwardly and downwardly turned portion 13 and the inwardly and upwardly turned portion 14, there is disposed around the armlet an elastic 80 member 17 which is secured to the outer portion 18 of the tunnel by means of stitches at 19 and 20. These stitches preferably extend longitudinally of the armlet so that they will not interfere with the tendency of the elastic 85 member 17 to hold the lower portion of the armlet at its tunnel 16, with folds extending longitudinally of the armlet and as illustrated in Figures 1 and 2 of the drawing.

In wearing the armlet it is adjusted on the 90 arm of the wearer, as illustrated in Figure 1, the elastic member 17 serving to hold the lower portion of the armlet at the wrist of the wearer, it being possible to wear this armlet with or without gloves, but preferably the 95 armlet will be worn with gloves, as illustrated in Figure 1. When a glove 21 is also worn, the upper portion 22 of the glove will preferably be disposed under and within the lower portion of the armlet A, where it will 100

be yieldingly held by action of the elastic member 17, which serves to hold the lower portion of the armlet in position to yieldingly engage an upper portion 22 of the glove at the wrist of the wearer.

6. In the modified form of the invention illustrated in Figure 4, the armlet B has an opening 23 which extends through its lower edge 24, there being securing means for holding the sides of the armlet B at its opening 23 close together. Preferably a button 25 is secured to the armlet at one side of its opening 23 and a buttonhole 26 is made in the armlet at the other side of its opening 23, so that when the armlet is adjusted on the arm of the wearer, the button may be disposed in the buttonhole 26 to hold the lower portion of the armlet 24 around and close to the wrist. When a glove is worn with the armlet B the glove will be adjusted in position with its portion 22 disposed at the wrist, when the lower portion of the armlet B may be secured against the upper portion 22 of the glove by means of the button 25 and the buttonhole 26. Preferably the button 25 and the buttonhole 26 are at the inner side of the armlet and the outer side of the armlet is preferably provided with an extending portion 27 which will be disposed at the back of the glove.
30. It will be understood that the invention includes an armlet having a wrist end with any desired means for holding portions of the wrist end relatively to each other. It will also be understood that the armlet may be decorated with any kind of design which may be produced by any desired means and with any desired material.

What is claimed is:—

1. An armlet for women's evening dress wear having a wrist end, the armlet being provided with an outwardly disposed tunnel at its wrist end, and an elastic member disposed in the tunnel and secured to the outer portion of the tunnel to form folds at the wrist end.
2. An armlet for women's evening dress wear having a wrist end, the armlet at its wrist end extending outwardly and upwardly, then outwardly and downwardly and then inwardly and upwardly where it is secured to the body of the armlet to form a tunnel, and an elastic member disposed in the said tunnel and secured to the outer side thereof.
3. An armlet for women's evening dress wear having a wrist end, the armlet at its wrist end extending outwardly and upwardly, then outwardly and downwardly and beyond the first mentioned outwardly-extending portion and then inwardly and upwardly where it is secured to the inner side of the body of the armlet to form a tunnel, and an elastic member disposed in the said tunnel below the wrist end, the elastic member being secured to the outer portion of the tunnel.

4. An armlet for women's evening dress wear having a wrist end, the armlet at its wrist end extending outwardly and upwardly, then outwardly and downwardly and beyond the first mentioned outwardly-extending portion and then inwardly and upwardly where it is secured to the inner side of the body of the armlet to form a tunnel, and an elastic member disposed in the said tunnel and secured to the said downwardly-extending portion of the tunnel. 70

5. An armlet for women's evening dress wear having a wrist end, the armlet at its wrist end extending outwardly and upwardly, then outwardly and downwardly and beyond the first mentioned outwardly-extending portion and then inwardly and upwardly where it is secured to the inner side of the body of the armlet to form a tunnel, and an elastic member disposed in the said tunnel below the said wrist end and secured to the said downwardly-extending portion of the tunnel. 80

6. An armlet for women's evening dress wear having a wrist end, the armlet extending from its upper portion to its wrist end continuously, smoothly and uninterruptedly, the armlet at its wrist end extending outwardly and upwardly, then outwardly and downwardly and beyond the first mentioned outwardly-extending portion and then inwardly and upwardly where it is secured to the inner side of the body of the armlet to form a tunnel, and an elastic member disposed in and extending around the said tunnel and secured to the outer side of the said tunnel, to form folds in the outer side of the tunnel and to press the inner side of the tunnel inwardly. 90

7. An integral flexible armlet for women's evening dress wear having a wrist end, the armlet extending from its upper portion to its wrist end continuously, smoothly and uninterruptedly, the armlet at its wrist end extending outwardly and upwardly, then outwardly and downwardly and beyond the first mentioned outwardly-extending portion and then inwardly and upwardly where it is secured to the body of the armlet to form a tunnel, and an elastic member disposed in and extending around the said tunnel, the elastic member being disposed below the said wrist end and being secured to the outer side of the said tunnel. 100

Signed at New York, in the county of New York and State of New York, this 17th day of March, A. D. 1931.

IRWIN STEINBERGER.
